*Primary Examiner—Jeffrey Asch
Attorney, Agent, or Firm—Pollock, Vande Sande & Priddy***[57] CLAIM**

The ornamental design for an audible signal for alarm units, as shown and described.

DESCRIPTION

FIG. 1 is a perspective view of an audible signal for alarm units showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof (of which a right side elevational view would be a mirror image);

FIG. 7 is a cross-sectional view thereof taken on line 7—7 of FIG. 2, an internal mechanism of which is not shown;

FIG. 8 is a cross-sectional view thereof taken on line 8—8 of FIG. 5, an internal mechanism of which is not shown;

FIG. 9 is a cross-sectional view thereof taken on line 9—9 of FIG. 5, an internal mechanism of which is not shown; and

FIG. 10 is a cross-sectional view thereof taken on line 10—10 of FIG. 5 an internal mechanism of which is not shown; and,

FIG. 11 is a cross-sectional view thereof taken on line 11—11 of FIG. 5, an internal mechanism of which is not shown.
